UNITED STATES PATENT OFFICE.

HENRY J. PILS, OF WASKISH, MINNESOTA.

SNOWPLOW.

Application filed June 14, 1927. Serial No. 198,802.

This invention relates to a snow plow and has for its primary object the construction and arrangement of parts whereby the travel of the snow plow over the road is accurately guided without in any way interfering with the efficient operation of the snow plow in the removal of snow or other matter.

Another object of the invention is the provision of runners for the snow plow of novel construction whereby adjustment thereof will control the engageable action of the scraper with the snow and the direction of travel of the snow plow.

Another object of the invention is the construction and arrangement of the novel guiding structure whereby the scraper is held in the proper direction of travel at all times irrespective of the direction of pull of the horses or tractor or other power apparatus connected to the plow.

Besides the above, my invention is distinguished in the use of a pair of runners one vertically adjustable for controlling the action of the scraper, the other horizontally adjustable for controlling the direction of travel of the plow.

With these and other objects in view, the invention will be better understood from the following detailed description taken in connection with the accompanying drawings, wherein:

Figure 1 is a top plan view of the snow plow,

Figure 2 is a side elevation,

Figure 3 is a front elevation,

Figure 4 is a cross sectional view,

Figure 5 is a detailed perspective view of a portion of the scraper and its associated parts,

Figure 6 is a detailed cross sectional view of the adjustable runner and its associated parts.

Again referring to the drawings illustrating one of the many constructions of my invention, the numeral 1 designates a platform shown in this particular as of triangular formation and constructed of a plurality of beams, one hereinafter known as the main beam and designated by the numeral 2 and extending in the direction of travel of the snow plow and directly secured to a laterally extending inclined beam 3. Mounted on the beams are the usual floor boards 4 for supporting the operator or weights if found advantageous to increase the weight of the snow plow.

The numeral 5 designates the scraper or mould board of the snow plow and it will be noted that this scraper is of curved formation in cross section and is supported to extend at an angle to the main beam 2, and for the purpose of supporting the scraper in such an inclined position in a very substantial manner I provide the beam 3 and a plurality of brackets 6 effectively riveted to the scraper and secured to the platform 1. It will be noted that the scraping edge 7 of the scraper parallels the ground and for the purpose of adjusting the scraping edge 7 relative to the ground for controlling the action of the scraper upon the snow, I provide an adjustable runner or shoe 8 which is not only capable of changing the position of the scraper, but supports the platform for sliding movement over the snow. This adjustable runner 8 is flexibly and adjustably connected to the platform to permit vertical adjustments thereof and to accomplish this desired result, I have shown a rear link 9 pivotally connecting the runner to the platform and a forward link 10 also pivotally connecting the runner to the platform. These links are so connected and arranged that the runner is effectively secured against horizontal displacement but are adjustable to allow the runner to have its required vertical adjustments by the manipulation of my improved control mechanism designated in its entirety by the numeral 11.

This control mechanism consists of a slide 12 having a pivotal connection 13 with the shoe and also an adjustable pivotal connection 14 with the control lever 15. This control lever 15 has a flexible connection 16 with the incline beam 3 of the platform, so that upon raising and lowering the lever 15 from the connection 16 the slide 12 will be raised and lowered and for the purpose of guiding such movements of the slide 12, I have shown the latter slidably mounted in an opening 17 in the platform. The lever 15 has a cooperative relation with a vertically extending ratchet bar 18, the teeth of which are so disposed as to be selectively engaged by the lever 15 in the adjustment thereof for effectively and rigidly supporting the shoe in any one of its adjustable positions. An end plate 19 is secured to the forward end of the scraper so as to prevent accumulations from passing over this edge of the scraper and further to materially reinforce the scraper at this point.

To complete the invention, I provide a novel construction of guiding device design-

nated in its entirety by the numeral 20. This guiding device or structure 20 includes the heretofore mentioned beam 2 and an adjustable steering runner 21 and a shoe 22, the latter secured to the under surface of the rear portion of the beam 2 and including in its construction a downwardly extending rib 23 for penetrating engagement with the snow or other material in contact therewith. A very important feature of my invention is the construction and design of the steering runner 21, whereby the snow plow may be effectively steered in its travel so as to assure the proper position of travel of the snow plow irrespective of slight change in the direction of pull thereof. This steering runner 21 also includes a downwardly projecting rib 24 for penetrating the snow or other material coming in contact therewith to offer a certain resistance to the lateral displacement of the steering runner and this resistance is relied on to hold the plow in its proper direction of travel. A clevis 25 forms a component part of the steering runner and this clevis and runner are directly secured together and pivotally secured to the beam by means of the pivot bolt 26.

Due to the angular relation of the scraper and the main beam 2, it will be appreciated that in the travel of the snow plow in a direction corresponding to the direction of the extension of the beam 2, the snow will be effectively accumulated by the scraper for discharge from the outer end portion of the scraper which outer end portion is disposed rearwardly of the snow plow. It is of great advantage in the proper removal of snow accumulations to vary the action of the scraper upon the snow which the operator may effectively accomplish by adjusting the lever 15, which causes the raising and lowering of the runner 8, depending upon the direction of travel of the lever. When the runner has been properly adjusted to bring about the most effective engagement between the scraper and the snow, the lever is thrown into an interlocking engagement with the ratchet bar 18 and thus the parts are effectively locked in their proper adjusted positions, but capable of quick adjustment should occasion arise. In the travel of the snow plow in engagement with the snow there is a tendency of the snow plow to move out of its proper direction of travel due to the side thrust of the snow against the scraper and to overcome this effect, and assure the proper travel of the snow the steering runner 21 and the shoe 22 are arranged in alignment corresponding to the direction of travel of the snow plow so that the ribs thereof penetrating the snow will offer a certain amount of resistance to the side

thrust of the snow plow to prevent displacement thereof.

It is of course to be understood that various other types of scrapers may be designed for use with my improved snow plow and various other constructions of adjusting mechanisms may be used for raising and lowering the scraper relative to the ground, and besides the steering device may be constructed in various other manners than illustrated and therefore, I do not desire to be limited in any manner except as set forth in the following claims.

What I claim is:

1. A snow plow comprising a platform including a main beam extending in a direction of travel of the snow plow and in contact with the snow, a scraper supported at an incline by said platform with relation to said main beam, an adjustable runner connected under said platform to be adjusted vertically to control the position of the scraper relative to the ground, and means for adjusting said runner, said means consisting of a slide pivoted to the runner and slidably mounted in the platform and an adjustable lever having a pivotal connection with said slide. 75

2. A snow plow comprising a substantially triangular-shaped platform including a main beam extending in the direction of travel of the snow plow, a scraper of curved formation in cross section and supported by the platform to extend at an angle to said main beam, an adjustable runner having a swinging connection both with the main beam and with 90 said scraper, a slide connected to the runner and mounted in said platform, a lever swingingly connected to the platform and pivotally connected to said slide and a rack bar supported by the platform and engageable with 95 said lever for holding the latter in any one of its adjusted positions. 100

3. A snow plow comprising a substantially triangular-shaped platform including a main beam extending in the direction of travel of the snow plow, a scraper of curved formation in cross section and supported by the platform to extend at an angle to said main beam, an adjustable runner having a swinging connection both with the main beam and with 105 said scraper, a slide connected to the runner and mounted in said platform, a lever swingingly connected to the platform and pivotally connected to said slide and a rack bar supported by the platform and engageable with 110 said lever for holding the latter in any one of its adjusted positions, a shoe supported by the rear portion of the main beam and a steering runner pivotally supported by the front end of the main beam. 115

In testimony whereof I affix my signature.
HENRY J. PILS.
